UNITED STATES PATENT OFFICE

EDWIN FITCH NORTHRUP, OF PRINCETON, NEW JERSEY, ASSIGNOR TO AJAX ELECTROTHERMIC CORPORATION, OF AJAX PARK, NEW JERSEY, A CORPORATION OF NEW JERSEY

INDUCTION ELECTRIC FURNACE

Application filed July 16, 1929. Serial No. 378,622.

My invention relates to furnaces which are intended to hold a content or charge of material which is easily contaminated by the crucible used.

5 A purpose of the invention is to make a furnace crucible of sectional construction comprising small light sections which are easily formed and easily handled.

10 A further purpose is to form a crucible of horizontally divided sections, electrically conducting or non-conducting according to the needs of the furnace.

15 A further purpose is to apply sectional furnace construction to electric induction furnaces, making each section a separate inductor secondary and placing the secondaries electrically in parallel.

20 A further purpose is to provide a furnace made up of sections which may be held together by their weight and which may be sealed further and additionally secured in position by a surrounding tamped finely divided refractory.

25 A further purpose is to provide a furnace made up of a series of rings divided in horizontal planes, permitting variation in the shape of the furnace by change in the rings selected.

30 A further purpose is to provide a furnace particularly suited to the melting of glass of special quality.

35 A further purpose is to provide a furnace which is readily manufactured from materials which are difficult to cast in large units but which may be very desirably free from contaminating ingredients.

Further purposes will appear in the specification and in the claims.

40 I have preferred to illustrate my invention by one general form only, selecting a form which is practical, efficient and relatively inexpensive and which is well suited to the service for which it is intended.

45 Figures 1 and 3 are central vertical sections of slightly different forms of my invention.

Figure 2 is a section taken upon line 2—2 of Figure 1.

50 Figure 4 is a perspective view of one of the rings of my furnace.

In furnace practice considerable difficulty is found in handling some of the charges because they are quite sensitive to contamination by the material of the crucible or other container in which they are held. In 55 some arts this seriously interferes with proper heating, melting and holding of the charge.

One example of this is found in the glass art where high grade glass intended for 60 optical uses or for Pyrex glass has been found to be very easily contaminated by the usual crucible materials.

Glass is electrically non-conducting and the heat must be developed in the container. 65 Glass melts at a low enough temperature to be melted within a metal pot or crucible, but the metals which are best suited otherwise for crucible purposes are not free from contaminating effect upon the glass. On the 70 other hand some of the best metals from the standpoint of freedom from contamination of the melt present difficulty in casting which makes it difficult to cast an entire crucible in one piece and hence in the past have not 75 been available for furnace crucible purposes. One excellent example of this lies in the various alloys of tungsten carbide and nickel which are non-contaminating with respect to glass and excellent for the purpose in 80 varying percentages of carbide and nickel and operate well with 80% tungsten carbide and 20% nickel. This alloy is difficult to 85 cast in large units.

My invention is designed to make metals 85 and such alloys fully available for furnace purposes by providing for sectional furnace construction. It offers a sectional construction which is simple and inexpensive and which has many advantages in addition to 90 its adaptability for use with special metals.

Describing in illustration and not in limitation:—

The furnace illustrated is made up of 95 rings which can be separately cast and finished and can be built up into crucible form by mounting one ring upon another until the desired furnace height is reached.

Crucible 5 is made up of a base 6 and a 100 plurality of rings 7 which may be of equal

diameter to make a cylindrical crucible, as in Figure 1, or of different diameter as at 7' in Figure 3 or shape to give any desired contour to the furnace.

5 The invention is particularly well suited to the coreless type of electric induction furnace, such as in Figures 1 and 3.

In these figures I have shown a coreless type furnace inductor 8 surrounding the 10 composite crucible and supplied with electric current as conventionally illustrated by leads 9 and 10 across which is placed power-factor-corrective capacity 11. The turns of the inductor may be water-cooled if desired 15 whenever the temperature to be attained justifies it.

The coil is shown as insulated interiorly at 12 by any suitable shell 13, such as mica-nite, and is spaced from the crucible at 14 by 20 any suitable material or materials which will heat, insulate and preferably also form a supplemental protection against leakage of the melt between the rings or sections. A finely divided refractory such as magnesium 25 oxide, tamped to place, has been found to give excellent results. It also holds the rings down more effectively than does the weight of the rings alone.

At the top the space above the crucible 20 and refractory is capped by a moulded ring 15 with which the furnace cover—not shown—may engage.

Beneath the crucible the refractory rests upon any suitable bottom 16 which is extended to carry the coil at 17.

The furnace is encased within an outer frame 18 supported by trunnions 19 from links 20.

The outer frame or shell 21 may be of non-magnetic material as in Figure 3, or may be magnetic and be protected from stray field by any suitable means such as magnetic return circuit 22. Such a magnetic return circuit should be laminated and may conveniently extend across beneath the bottom of the furnace as well as up the sides at any desired number of locations about the furnace circumference.

I have shown a conventional finish of the 50 upper part of the furnace in the spacing of the outer frame or shell 21 from the refractory 15 by a ring 23 of some such material as asbestos lumber.

In Figure 3 the bottom is supported from 55 the lower part of the shell by a spacer 24.

It will be evident that the subdivision of the crucible into sections is desirable whatever the sections and that subdivision along horizontal parallel planes provides secondary paths in parallel within which current will be induced by the normal vertical furnace inductor. The resultant structure is therefore of maximum advantage from standpoints both of construction and operation. It further reduces repair and replace-

ment costs since in case of injury the particular section injured alone will need be replaced.

For most of the services required the engagement of the sections sufficiently protects 70 against leakage of molten charge between them requiring no additional holding of the sections.

It will be noted that the tamped refractory performs a multiple function in that it provides heat insulation, additionally insures against displacement of the sections from their sealing contact and closes the space about the sections against passage of leakage charge which may tend to pass through the 80 joints between the sections.

The holding power of the tamped refractory and of the refractory section at the top of the furnace are quite desirable to hold the sections against relative movement during 85 pouring.

In view of my invention and disclosure variations and modifications to meet individual whim or particular need will doubtless become evident to others skilled in the art to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. A furnace crucible comprising a bottom section and metal rings resting upon the bottom and successively upon each other to make up the side walls of the crucible.

2. A furnace crucible having side walls of electrically conducting metallic rings adapted to rest one upon another.

3. A furnace crucible having side walls of electrically conducting metallic rings adapted to rest one upon another and free from contaminating effect upon the intended melt.

4. An induction electric furnace crucible comprising a bottom section, a plurality of detachable short electrically conducting metallic rings resting one on another and a coreless inductor surrounding the crucible and adapted to induce secondary flow of current 110 in the sections in parallel.

5. In an electric induction furnace, a crucible made up of horizontally disposed metallic rings resting one upon another, an inductor coil surrounding the crucible and finely divided refractory rammed between the coil and crucible and adapted to hold the rings in position by firm engagement with their exterior surfaces.

6. A crucible comprising a bottom section and a plurality of rings together forming side walls, a refractory material outside the rings, an inductor coil surrounding the refractory and a magnetic circuit for return flux outside of the inductor.

7. A crucible ring adapted to form part of a furnace body and comprising an alloy of tungsten carbide and nickel.
8. A crucible ring adapted to form part of a furnace body and comprising an electrically conductive metal difficult to cast in large units.
9. A glass melting furnace comprising a bottom section and rings of an alloy of tungsten carbide and nickel, a refractory packed about the crucible and a furnace inductor surrounding the refractory and crucible.
10. A glass melting furnace comprising a bottom section and rings of an electrically conducting metal non-contaminating to glass, a refractory packed about the crucible and a furnace inductor surrounding the refractory and crucible.
